UNITED STATES PATENT OFFICE.

ANDREW LANGSTAFF JOHNSTON, JR., OF NEW YORK, N. Y., ASSIGNOR, BY MESNE ASSIGNMENTS, TO OFF'N'ON CHAIN CORPORATION, OF NEW YORK, N. Y., A CORPORATION OF DELAWARE.

WIRE CHAIN LINK.

Application filed December 8, 1920. Serial No. 429,072.

To all whom it may concern:

Be it known that I, ANDREW LANGSTAFF JOHNSTON, Jr., a citizen of the United States, residing at New York, in the county of New York and State of New York, have invented certain new and useful Improvements in Wire Chain Links, of which the following is a full, clear, and exact description, such as will enable others skilled in the art to 10 which it appertains to make and use the same.

This invention relates to wire chain links, and more particularly to such links bent from a single strand of wire whose two ends 15 form a double-strand eye.

It is an object of the invention to provide a simple, reliable chain in which the links are so shaped as to avoid picking up foreign matter and catching or cutting adjacent surfaces or parts.

It is another object of the invention to provide an improved chain link bent from a single length of wire and having an eye so coiled as to resist distortion or fracture under strain.

A further object of the invention is to provide a chain link which will be structurally superior and functionally advantageous.

Other objects will be in part obvious and 30 in part noted hereinafter.

In the accompanying drawing forming part of this specification,—

Figure 1 is a side view of a portion of a chain embodying a preferred form of the invention,

Fig. 2 is an edge view of the same;

Fig. 3 is an enlarged end view of one of the links; and

Fig. 4 is an enlarged section taken on the 40 line 4—4 in Figure 1.

The improvement consists particularly in the formation of the eye of each link through which a succeeding link is threaded.

Referring to the drawings, each link 1 is 45 manufactured from suitable chain metal having a round or other cross-section and is bent in a substantially rectangular formation to form a large loop which is threaded through the eye of another link. In the present instance the eye of a link is formed in the following manner:

The two sides of the large loop are bent inwardly, offset, and then looped in opposite

directions to form contiguous coils 2 and 3 substantially circular in shape. The free 55 ends of these coils are further bent to encircle and bind the neck of the coils; that is, the contiguous, offset portions between the large loop and the eye of the link. The extremities 4 and 5 rest snugly against the neck 60 of the coils, and as shown in the drawings, substantially lie within the contour of the wire forming the loop and the coils, so that no free ends are exposed.

The method of forming the coils 2 and 3 65 is best shown in Figs. 3 and 4. The neck portion of each coil (the wire merging from the two sides of the main loop to form the coils) is substantially encircled by the free end of each coil so that the neck is gripped 70 within the opposed U-shaped transverse terminals of the wire and lateral separation of the eyes or spreading of the link sides is effectively prevented. The eyes are in contact throughout and coil in opposite directions so that every curve in one of the strands from the point where the two sides of the loop meet is reinforced by a similar curve in the other strand. An eye so formed 75 is stronger than the wire itself, since at no portion of the link will the strain be borne by a single strand of wire. Furthermore, an eye so reinforced affords a maximum of frictional resistance to distortion with a minimum of material, thus tending to maintain 80 its perfect alignment.

By the construction described a compact link having rounded contours is provided 90 without the use of extra parts, and the free ends of wire are guarded within the surfaces of the coils so that recesses in which foreign matter might be lodged and projecting parts which might damage adjacent surfaces are avoided.

Since alterations might be made in the 95 above construction without departing from the spirit or scope of the invention, it is intended that all matter contained in the above description or shown in the accompanying drawings shall be interpreted as illustrative 100 and not in a limiting sense.

Having described my invention, what I claim as new and desire to secure by Letters Patent is:—

1. A chain link comprising a strand of 105 material bent to form an elongated loop, the

ends of said strand being separately looped in directions opposite to each other to form contiguous coils, and each end being bent to encircle the necks of both said coils.

5. 2. A chain link comprising a strand of material bent to form an elongated loop, the ends of said strand being separately looped to form substantially circular coils, and wrapped transversely about the necks of both coils so formed, every curve of each said end being paralleled and reinforced by a similar curve of the other end.

3. A chain link comprising a strand of material bent to form a substantially rectangular loop, the ends of said strand being separately looped to form coils, the coils so formed being contiguous, each end of said strand also terminating in transversely disposed oppositely extending U-shaped portions and embracing the necks of both said coils, the extreme ends of said strands lying

within re-entrant angles of the contour of said loop and said coils.

4. A chain link comprising a single strand of material bent to form a main loop and an auxiliary loop, the plane of said auxiliary loop being substantially perpendicular to the plane of said main loop; the auxiliary loop being formed by bringing together the free ends of said main loop, bending said ends in opposite directions to form contiguous coils, and further bending said ends to encircle the neck of said coils in a plane substantially perpendicular to the planes of said main loop and said auxiliary loop.

In testimony whereof I affix my signature, in the presence of two witnesses.

A. LANGSTAFF JOHNSTON, JR.
